COVER FOR A SUGAR CONTAINER OR THE LIKE

James B. Swett, Barrington, R.I., assignor to Rexall Drug and Chemical Company, Los Angeles, Calif., a corporation of Delaware

Filed Oct. 1, 1962, Ser. No. 71,946

Term of patent 14 years

(Cl. D44—15)

FIG. 1

FIG. 2

FIG. 3

FIG. 4

FIG. 5

FIG. 6

FIGURE 1 is a top perspective view of a cover for a sugar container or the like showing my new design;
 FIGURE 2 is a top perspective view thereof, with the lids in open position;

FIGURE 3 is a plan view thereof;

FIGURE 4 is a side elevation view thereof;

FIGURE 5 is an end elevation view thereof, and,

FIGURE 6 is a fragmentary top plan view, with a lid portion.

The characteristic features of my design for the cover for a sugar container disclosed reside in the opposed hinge

closure flaps having configurations substantially as shown.
 A sugar bowl is shown by means of broken lines in FIGS. 1, 2, 4, and 5 for illustrative purposes only.

I claim:

The ornamental design for a cover for a sugar container or the like, as shown and described.
